CLAIM

The ornamental design for a bioreactor vessel, as shown and described.

DESCRIPTION

FIG. 1 is a top perspective view of the bioreactor vessel of the invention;

FIG. 2 is a bottom perspective view of the bioreactor vessel of FIG. 1;

FIG. 3 is a right side view of the bioreactor vessel of FIG. 1;

FIG. 4 is a left side view of the bioreactor vessel of FIG. 1;

FIG. 5 is a front view of the bioreactor vessel of FIG. 1;

FIG. 6 is a rear view of the bioreactor vessel of FIG. 1;

FIG. 7 is a top view of the bioreactor vessel of FIG. 1; and,

FIG. 8 is a bottom view of the bioreactor vessel of FIG. 1. The broken lines located within the circle located on the top of the bioreactor vessel and seen in FIGS. 1 and 7 are
